CLAIM

The ornamental design for a mounting tool for a guide tube for cables in a fire wall, as shown and described.

DESCRIPTION

FIG. 1 is a front perspective view from above of a mounting tool for a guide tube for cables in a fire wall showing out new design,

FIG. 2 is a rear perspective view thereof from below,

FIG. 3 is a top plan view thereof,

FIG. 4 is a bottom plan view thereof,

FIG. 5 is an elevational view from the left side of the tool, the view from the right side being a mirror image thereof,

FIG. 6 is a front elevational view thereof, and

FIG. 7 is a rear elevational view thereof.

FIG. 1

FIG. 2

FIG. 3

FIG. 4
